UNITED STATES PATENT OFFICE.

JOHN W. MOON, OF BUTLER, PENNSYLVANIA, ASSIGNOR TO FRETZ-MOON TUBE COMPANY, OF BUTLER, PENNSYLVANIA, A CORPORATION OF PENNSYLVANIA.

APPARATUS FOR MANUFACTURING CONTINUOUS TUBING FROM SEPARATE REELS OF SKELP.

Application filed February 27, 1925. Serial No. 12,036.

In patents issued to me December 4, 1923, No. 1,476,537 and No. 1,476,632, I have set forth a process and apparatus for producing continuous tubing from an endless length of flat skelp which continuously travels through an elongated furnace in which every point in its length is gradually heated up to or near a welding heat, the skelp being formed into a tube and its edges welded together by bending and welding rolls located just in front of the delivery mouth of the furnace; these bending and welding rolls and sizing rolls arranged beyond the bending and rolling rolls operating to pull the skelp through the furnace. The skelp is received for use rolled on reels, and in order to deliver the skelp to the furnace in a continuous manner, it is necessary to weld the rear end of one roll of skelp to the front end of a fresh roll of skelp. In my said patents, this operation is effected in the following manner. During the feeding of skelp from a reel positioned just back of the furnace, workmen unreel a length of skelp from said reel and welded the rear end of such unreeled portion to the front end of a fresh roll of skelp, the length of skelp unreeled from the first roll in the meantime continuing to feed to the furnace. The fresh reel was then placed in the same position as the original reel. Subsequently, by repeating the same operation, the rear end of the skelp on the second reel was welded to the front end of the skelp on a third reel.

In handling skelp of the larger sizes, two workmen are required to effect the unreeling, and the operation is quite laborious. I have devised an unreeling machine which is adapted to perform the major part of the work of unreeling and by whose use the actual physical labor is materially reduced. I have also so arranged and operated the unreeling machine as to substantially improve the mode of operation. In the drawings, which show a preferred embodiment of my invention—

Fig. 1 is a plan view of the reeling-out machine of the apparatus.

Fig. 2 is a front elevation of same.

Fig. 3 is a sectional elevation on the line 3—3 of Fig. 1.

Fig. 4 is a diagram of the complete apparatus.

The reeling-out (or unreeling) machine

will first be described. From the base of the machine extend posts *a* to which are secured a frame *b* having housings for the shaft of a driving roll *c*. Another roll *d* has its shaft turning in housings carried by a frame *e* secured to rockable posts *f*. Posts *f* are supported on plates *g*, which are pivotally mounted on a shaft *h*, to which is also pivoted arms *i* having at their free ends a treadle *j*. Links *k* connect arms *i* with rockable posts *f*.

By lifting the treadle by hand, roll *d* may be swung away from roll *c*. Unless the treadle be so lifted, roll *d* will swing toward roll *c*.

The shaft of roll *c*, through a pair of bevel gears *m*, is driven from a shaft *n*, which, through spur gears *o*, is driven by a motor *p*.

As shown, the rolls *c* and *d* are adapted to grip the edges of the skelp *x*, but the invention is not limited to rolls adapted to engage the skelp edgewise, nor to rolls one of which is positively driven and the other of which is an idler, nor to the precise other details of construction described; these being only structural features of a preferable embodiment of the invention.

The operation will be understood by reference to the diagram of Fig. 4 in connection with the following description.

Back of the furnace *r* are supporting pins *t* on each of which is adapted to be slipped a reel of skelp. Back of these reel supports is an electric welding contrivance *u* and back of that a reeling-out machine like that hereinbefore described and which, as an entirety, I have indicated by the reference letter *v*. Let it be assumed that skelp *x* is continuously entering the furnace *r* and unwinding from a reel *y* of skelp on one of the pins *t*. The skelp may be assumed, as it unwinds from reel *y*, to travel back through the rolls of the reeling-out machine *v* and thence around and forward toward the rear of the furnace, a loop of considerable size being formed back of the machine *v*. It should be understood that the skelp is pulled through the furnace by the tube-forming mechanism in front of the furnace, this mechanism being diagrammatically shown, and comprising bending and welding rolls 10 and sizing rolls 11 and 12.

From another reel *z* of skelp, a few feet

are unwound to bring the forward end of the skelp to the welding device *u*. When the rear end of the skelp from reel *y* reaches the welding device *u*, the motor *p* of the reel-out machine is stopped and the rear end of the skelp from reel *y* is welded to the front end of the skelp unwound from reel *z*.

During the welding operation, the skelp, of course, continues to feed forward to the furnace. After the weld is made, the rolls *c* and *d* are held inactive (by the stopping of motor *p*) until the weld is fairly cold. Then the motor is again started, pulling the welded joint through the rolls.

Reel *y* is removed and a fresh reel is substituted therefor, the front end of the skelp thereon being subsequently welded to the rear end of the skelp on reel *z*, just as the front end of the skelp on reel *z* was welded to the rear end of the skelp on reel *y*.

The rolls *c* and *d* are adapted to unwind the skelp at a faster rate than the skelp is pulled through the furnace, so as to gradually increase the length of skelp between machine *v* and the furnace until the machine is stopped for the time required to perform the welding operation, during which stoppage the excess length of skelp between the machine *v* and the furnace is taken up by the continued travel of the skelp through the furnace.

While the skelp is passing between rolls *c* and *d*, the operator will usually maintain a slight foot pressure on the treadle to insure against the skelp jumping out of the rolls due to kinks in the skelp.

In starting the operation of the plant, the treadle *j* of the reeling-out machine is lifted to separate the rolls *c* and *d* and allow the end of the first reel of skelp to be inserted into the grooves of the rolls; but after the plant is in operation, the rolls are maintained in operative relation with the skelp, which travels therethrough continuously except during the welding operation.

Having now fully described my invention,

what I claim and desire to protect by Letters Patent is:

1. In an apparatus for manufacturing a continuous length of tubing from separate reels of skelp, the combination with a furnace through which the skelp is adapted to travel, means to form the skelp into tubing and to continuously draw the skelp through the furnace, means at the rear of the furnace to hold reels of skelp, a welding contrivance, a reeling-out machine adapted to engage the skelp from the reels and unwind it from the reels for delivery to the furnace, and driving means for said machine adapted to operate said machine to unwind said skelp at a higher rate of speed than that at which it is pulled through the furnace and adapted to be stopped to allow the rear end of the skelp from one reel to be welded to the front end of the skelp from another reel.

2. The apparatus defined in claim 1 wherein the welding machine comprises two rolls, one of which is relatively movable from the other to allow skelp to be inserted between them and toward the other to allow the skelp to be gripped between them.

3. The apparatus defined in claim 1 wherein the welding machine comprises a fixed roll, a movable roll, an upwardly extending movable-roll support, a laterally extending arm, means connecting said arm and roll support whereby when the arm is lifted the movable-roll support is swung away from the fixed roll to allow skelp to be inserted between the rolls, and a treadle on the laterally extending arm which is adapted to be pressed down to cause the skelp to be gripped between the rolls with a regulatable pressure.

In testimony of which invention, I have hereunto set my hand, at Philadelphia, Pennsylvania, on this 23rd day of February, 1925.

JOHN W. MOON.
